(57) **CLAIM**

The ornamental design for a divided dish, as shown and described.

DESCRIPTION

FIG. 1 is a top, front and right side perspective view of the design;

FIG. 2 is a bottom, front and left side perspective view of the design;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a reference view showing an example in which the design is coupled to a bowl.

The broken line illustration of environmental structure in the drawing is not part of the design sought to be patented.

1 Claim, 9 Drawing Sheets
